INVENTOR

UNITED STATES PATENT OFFICE.

ROBERT GAIR, OF NEW YORK, N. Y.

DESIGN FOR A BOX-STRIP.

41,275.

Specification for Design.

Patented Mar. 28, 1911.

Application filed January 27, 1911. Serial No. 605,138. Term of patent 7 years.

To all whom it may concern:

Be it known that I, ROBERT GAIR, a citizen of the United States, residing at New York, borough of Brooklyn, county of Kings, State of New York, have invented a new, original, and ornamental Design for Box-Strips, of which the following is a full, clear, and exact specification.

In the accompanying drawing, the figure

is a plan view of a box strip showing my design.

I claim,

The ornamental design for a box strip, as shown.

ROBERT GAIR.

Witnesses:

L. BEATTIE, Jr.,

RICHARD PFEIFER.
